Letters Patent No. 68,425, dated September 3, 1867.

IMPROVEMENT IN KNITTING MACHINES.

The Schedule referred to in these Letters Patent and making part of the same.

TO ALL WHOM IT MAY CONCERN:

Be it known that I, SAMUEL V. ESSICK, of Mansfield, in the county of Richland, and State of Ohio, have invented a new and useful Improvement in Machine for Knitting; and I do hereby declare that the following is a full and clear description thereof, reference being had to the accompanying drawings, and to the letters of reference marked thereon.

My invention relates to certain improvements in machinery for knitting, as hereinafter specified and represented. In reference to the accompanying drawings—

Figure 1 is a perspective view, representing the improved knitting machine with all its working parts arranged in order for operation.

Figure 2 is a sectional view of the main part of the machinery, showing the parts which form the stitches and fix them upon the cogs of wheel J.

Figure 3 is a sectional view of the main sliding piece.

Figure 4 is a sectional view of a lever, the point N of which strips off the old stitch and forms the new one on each cog of the wheel J.

Figure 5 is a sectional view of spring D.

L is a needle, which carries the thread over the cogs of wheel J, and through the stitch formed on the cog of said wheel J. This needle L is bevelled at the point on the top, and is straight on the under side. A is a lever, the point N of which strikes the inside of the cogs of wheel J, thus securing the stitch formed on the cog of said wheel J, and by the backward motion of said lever A the said stitch is drawn off the said cog, and at the same time the new stitch is formed on the said cog by being fixed on the cog while the old one is stricken off by the point of the lever A. D is a spring, working in connection with lever A in such a way that its point strikes between the thread and the needle L, and holds the thread while the needle is drawn backward, thus forming a new stitch. When this is done the lever A and spring D, being connected are drawn back together, which backward motion strikes off the old stitch and forms the new stitch upon the cog of wheel J. P is a spring, which holds down the lever A. T is a rod, connecting the main sliding piece B with the crank N''. E is a screw, surrounded by a spiral spring, which tightens the thread and causes the machine to knit a tight or loose web by means of the tightening or loosening of the screw, the thread being caused to pass between the said spring and the body of the machine in which the screw works. R is a rim, which is fastened to the main plate or body of the machine, and so arranged as to be movable, in order that different sizes may be substituted, and is used for holding the stitches on wheel J. F is a ratchet, which turns the cog-wheel J, being connected with the main sliding piece B. H is a square wheel, with a notch at each corner, which works in the lever A, carrying it forward over the stitches. M is the main plate, to which the machinery is attached.

The operation of my invention may be described as follows: The machine being first attached to a table or stand by means of a clamp, by the turning of the crank V all the working parts are set in motion. The needle L is carried forward through the stitch formed on the cog of wheel J. When it moves a sufficient distance the point of spring D strikes between the thread and the needle, the said point holding the thread until the needle is drawn back out of the way, when the point of lever A draws off the old stitch, and forms the new one on the cog by means of the backward motion of said lever A, the lever being drawn with the main sliding piece B. The ratchet F, by the forward motion of main slide B, is caused to move the cog-wheel J one cog at the taking of every stitch.

What I claim as my invention, and desire to secure by Letters Patent, is—

The needle L, constructed as described, the spring D, the main sliding piece B, the lever A, the wheel and rim J and R, the thread-holder E, the ratchet F, the spring P, and the cornered wheel H, all arranged and operating substantially as described and for the purpose set forth.

In testimony of which invention I hereunto set my hand in presence of—
